AXMINSTER TUBE FRAME

Oscar V. Payne, Leicester, Mass., assignor to
 Crompton & Knowles Loom Works, Worcester,
 Mass., a corporation of Massachusetts

Application July 3, 1948, Serial No. 36,983

10 Claims. (Cl. 139—10)

1

This invention relates to tube frames for Axminster looms and it is the general object of the invention to provide a tube frame having yarn tubes the yarn receiving mouths of which are disposed in such manner as to facilitate entry of large yarns and knots in the yarns.

An Axminster tube frame comprises an elongated carrier bar on which is rotatably mounted a spool wound with variously colored yarns arranged thereon in conformity with the pattern requirements of the fabric being woven. The bar is customarily provided with a row of aligned yarn tubes through which the yarns pass. According to prior practice it has been customary to make the yarn receiving mouths of the yarn tubes of a width not exceeding the space assigned to the tube measured in the direction of the length of the bar. Mouths formed in this manner are so narrow that it is difficult for thick yarns and knots to enter them.

It is an important object of the present invention to change the shape of the yarn receiving mouths and arrange them in such manner that each mouth can be wider than has been possible under prior practice. Certain forms of yarn receiving mouths made according to the invention have sharp corners or notches which may interfere with easy entrance of a knot and it is a further object of the invention to provide a guard or guide plate which will cover the aforesaid corners or notches and direct the yarns to the wider parts of the mouths.

The guard has perforations which register with the wider parts of the mouths, and it is another object of the invention to form the guard with funnel like flanges which project into the mouths to afford a smooth entrance for the yarns and also assist in maintaining the mouths in correct position.

With these and other objects in view which will appear as the description proceeds, the invention resides in the combination and arrangement of parts hereinafter described and set forth.

In the accompanying drawings, wherein two forms of the invention are set forth:

Fig. 1 is an elevation of one end of a tube frame made according to the preferred form of the invention, one of the loom chains which supports the tube frame being shown in cross section,

Fig. 2 is a vertical section on line 2—2 of Fig. 1,

Fig. 3 is a plan view looking in the direction of arrow 3, Fig. 1,

Fig. 4 is an enlarged detail horizontal section taken transversely through a group of yarn tubes on line 4—4, Fig. 1,

Fig. 5 is a view similar to Fig. 3 but shows the modification of the invention,

Fig. 6 is a front elevation looking in the direction of arrow 6, Fig. 5,

2

Fig. 7 is a view similar to a part of Fig. 2 but shows a yarn guard or guide which can be used with either form of the invention,

Fig. 8 is an enlarged vertical section on line 8—8, Fig. 7, and

Fig. 9 is a plan view looking in the direction of arrow 9, Fig. 8.

Referring particularly to Figs. 1 and 2, the tube frame F includes an elongated preferably tubular carrier bar 10 which may be of rectangular cross section. Extending upwardly from the carrier bar is a spool bearing 11 on which is rotatably mounted a yarn spool 12 wound with a number of tuft yarns Y arranged side by side. A bracket 13 also extends upwardly from the carrier bar to engage a transporting chain 14. A hook 15 normally cooperates with the chain 14 to support the tube frame, but when the latter is to be moved to tuft forming position the hook 15 is moved away from the chain by well-known clutch means not shown herein.

Extending along the front wall 20 of the carrier bar 10 and projecting downwardly therefrom is a series or row of yarn tubes T which may be arranged in small groups and attached to supporting plates 21 secured at 22 to the carrier bar. The lower ends of tubes T are formed with yarn delivery mouths 23 from which the yarns project downwardly when the tube frame is in the tuft forming or vertical position shown in Fig. 2.

The matter thus far described, except as noted hereinafter, may be of usual construction and manipulated in the customary manner in an Axminster loom. During a tuft forming operation the lower ends of the yarn Y will be fastened to the fabric being woven, after which the tube frame will be raised to pull off enough tuft yarn for the next row of tufts to be formed by the tube frame. As the tube frame rises the spool 12 will rotate and the yarns will pass down through the tubes T.

In carrying the present invention into effect provision is made for equipping each of the yarn tubes T with a yarn receiving mouth wider than those customarily found in tube frames made according to prior practice. As indicated in Fig. 4 the yarn tubes are seamless and may be made of any approved material, such as thin metal or a plastic. These tubes are secured to the plate 21 in any desired manner, as by welding or soldering when the tubes are metallic. When the tubes are plastic the plate 21 may be made of the same material so that it may be fused with the adjacent parts of the tubes.

As shown more particularly in Fig. 3 each tube T of the preferred form has an upwardly facing or opening yarn receiving mouth which is substantially circular in form. In order that the mouths

may be wider than the space assigned to their tubes measured lengthwise of bar 10 they are arranged in two rows as different distances from the carrier bar. Thus, in Fig. 3 alternate mouths 25 are spaced a substantial distance from the plate 21, whereas the intermediate mouths 26 are closer to and may be in direct engagement with the plate.

The mouths are preferably arranged in parallel rows which are parallel to the row of tubes T and also to the carrier bar and are so placed that the yarns leading from the spool are divided into two planes or sheets one of which designated at 27 enters the front mouths 25 and the other of which designated at 28 enters the rear mouths 26. Because of the arrangement of the mouths shown in Fig. 3 and the sheets of yarn shown in Fig. 2 it will be understood that adjacent yarns are at different distances from the carrier bar, and each yarn will be comparatively free to turn on itself without interference on the part of the adjacent yarns should this be necessary as a knot enters a mouth.

In the modification shown in Fig. 5 the yarn tubes T' are secured to a plate 30 similar to plate 21 and have yarn receiving mouths formed as isosceles triangles, the alternate mouths 31 having their bases 32 a substantial distance from the plate 30, while the intermediate mouths 33 have their bases 34 closely adjacent to and lying along the plate 30. As in the preferred form of the invention, adjacent triangular mouths have the centers of their areas located at different distances from the carrier bar. Referring more particularly to the triangular form of the mouths, the bases 32 of the alternate mouths 31 extend substantially parallel to but spaced from the plate 30, as indicated in Fig. 5.

In both forms of the invention the tubes will have their mouths formed by tools shaped to produce the round and triangular mouths shown respectively in Figs. 3 and 5. The mouths are integral with the tubes and are essentially contiguous with each other. In the modified form of the invention all of the space between the aligned bases 32 of the alternate mouths 31 and the plate 30 is available for the formation of mouths. Although this condition is not strictly true of the preferred form of the invention the mouths 25 and 26 have about as much usable area for receiving a knot as do the triangular mouths.

It will be apparent from both Figs. 3 and 5 that the mouths have sharp corners or notches which might interfere with the entrance of yarns. Thus, in the preferred form of the invention the mouths of the alternate tubes 25, while being essentially circular in section, are actually formed with a small restriction or notch 35 pointed toward the bar plate 21, and the intermediate mouths 26 are similarly formed with a restriction or notch 36. In like manner the apices 37 of the triangular mouths shown in Fig. 5 are formed as acute angles which might interfere with the entry of yarns.

In order to prevent the yarns and any knots in them from entering into the notches 35 and 36 of the circular mouths and the apices of the triangular mouths, provision is made to guide the yarns toward the wider parts of the mouths and away from those parts of the latter which might hold a knot.

A guard or guide G, shown more particularly in Figs. 7, 8 and 9, can be used with either of the forms of the invention shown in Figs. 3 or 5, but

is illustrated as adapted to mouths of the preferred form. The guard is made of a sheet metal strip 40 formed with an upright wing 41 which extends along and is secured to plate 21 by screws 22. Extending forwardly from the wing over the mouths is a guard plate or zone 42 the forward edge of which if desired may be bent down as at 43 along those edges of the mouths remote from the plate 21. The bent down part 43 is not essential, but when used will serve as means for entirely closing the mouths and keeping their thin edges from engagement with the yarns.

The guard zone 42 as shown in Fig. 9 is provided with a plurality of preferably circular perforations which are arranged in two parallel rows at different distances from the carrier bar. The perforations 46 of the front row correspond to the alternate mouths 25, while those of the rear row, shown at 47, correspond to the intermediate mouths 26. The perforations open downwardly into the wide parts of the mouths under them and guide yarns away from the restrictions 35 and 36. The center of each perforation is preferably over the center of the mouth area therebelow.

The plate or zone 42 may if desired have circular funnel shaped flanges 50 struck downwardly therefrom around each perforation to guide the yarns into the corresponding mouths. While the flanges 50 aid knots or large yarns to enter the mouths, they are not necessary in all forms of the invention.

In preparing the tube frame for use, and referring more particularly to the preferred form of the invention, the plates 21 with their attached tubes T will be arranged along the length of the carrier bar 10 so that the mouths 25 and 26 will be spaced at different distances from the plate. If the character of the yarn is such that it can readily enter the mouths without being held by the restrictions or notches 35 and 36 the tube frame may then be ready for use, but if the yarn is large it is desirable to apply the guard G to the carrier bar 10 in such position that its perforations will register with the mouths 25 and 26. The same general procedure will be followed when the triangular mouths are used, the perforations 46 and 47 registering with the centers of the areas of the triangles.

Each yarn tube, whether of the form shown in Fig. 3 or 5, will have a substantially straight yarn or thread passage 55 therethrough which leads from the corresponding receiving mouth to the delivery mouth therebelow. The yarn passage is located between side walls 56 and substantially straight front and back edges 57 and 58, respectively, of the yarn tube. The long dimension of the passage in cross section is perpendicular to the carrier bar. The mouths, whether circular or triangular, are symmetrical about a plane passing through the edges 57 and 58, as will be understood from Figs. 3 to 5.

It will be understood from Fig. 4 that the tubes T are uniformly spaced along the carrier bar and each tube has assigned to it a space corresponding to the gauge of the tube frame. Thus, if seven yarn tubes are employed to the inch, then $1/7$ " will be assigned to each tube, but it will be understood from an inspection of Figs. 3 and 5 that the mouths are considerably wider than the spaces occupied by or assigned to their tubes, and can accommodate larger yarns and knots than could the mouths as formerly made.

Referring to Fig. 3 it will be noted that the rear part of mouths 26 are substantially aligned with

the rear edge 53 of tube T, or an extension thereof, while the front part of mouth 26 is about midway between extensions of edges 57 and 58. A similar relation exists with respect to the front mouths 25. The center of each mouth is to one side of or eccentric relatively to the longitudinal axis of the corresponding thread passage, and it is this condition which permits the use of the mouths wider than those heretofore possible.

From the foregoing it will be seen that the invention provides simple means for providing the yarn tubes of an Axminster tube frame with yarn receiving mouths which are wider than has been possible in prior practice due to the fact that the mouths are located at different distances from the carrier bar and staggered so that each mouth will be at a distance from the carrier bar different from that of the adjacent mouths. This arrangement of the mouths permits the yarns to be divided into the two sheets or planes 27 and 28, thus affording more space around each yarn to permit a knot in it to turn if necessary to enter its receiving mouth. In the preferred form of the invention the mouths are substantially circular, whereas in the modified form the mouths are triangular, but in both forms of the invention the centers of the areas of the mouths are arranged in two rows or lines which are located at different distances from and preferably parallel to the carrier bar. Also, when heavy yarns are used and it is desired to protect them and any knots in them from the smaller corners of the yarn receiving mouths, the guard G may be used which has perforations registered with the wide parts of the mouths.

Having thus described the invention it will be seen that changes and modifications of the foregoing specific disclosure may be made without departing from the spirit and scope of the invention.

What is claimed as new is:

1. In an Axminster tube frame having a carrier bar provided with yarn tubes having yarn receiving mouths arranged in rows located at different distances from the carrier bar, and a guard supported by the carrier bar extending over said yarn tubes and having perforations registering with said mouths.

2. In an Axminster tube frame having a carrier bar provided with yarn tubes having yarn receiving mouths arranged in rows located at different distances from the carrier bar, and a guard plate supported by the carrier bar extending over and having funnel shaped openings therein registering with and opening downwardly into said mouths.

3. An Axminster tube frame having a carrier bar provided with a row of yarn tubes each of which has a yarn receiving mouth, the centers of the mouths of alternate tubes being farther from the carrier bar than the centers of the mouths of the intermediate tubes, and a sheet metal plate supported by the carrier bar extending over said mouths and having perforations registering with and opening downwardly into said mouths.

4. In an Axminster tube frame having a carrier bar, a yarn spool rotatably supported on the carrier bar over the latter, a series of yarn tubes mounted on and depending from the carrier bar, each yarn tube having an upwardly opening yarn receiving mouth, and a guard supported on the carrier bar extending over said tubes below the spool and having yarn receiving passages therethrough registering with and opening downwardly into said mouths.

5. An Axminster tube frame having a carrier bar provided with yarn tubes having yarn receiving mouths the centers of which are arranged in two rows parallel to and at different distances from the carrier bar, and a guard supported by the carrier bar extending over the yarn tubes and having perforations registering with said mouths.

10 6. In an Axminster tube frame having a carrier bar, a yarn spool rotatably mounted on the carrier bar over the latter, a series of yarn tubes mounted on the bar, each tube having a substantially circular yarn receiving mouth, said mouths having their centers arranged in two lines parallel to and at different distances from the bar, alternate mouths having their centers on one line and the intermediate mouths having their centers on the other line, and a guard extending over the yarn tubes and having perforations registering with said mouths.

15 7. In an Axminster tube frame having a carrier bar, a series of yarn tubes mounted on the bar, each tube having a substantially circular yarn receiving mouth, said mouths having their centers arranged in two lines parallel to and at different distances from the bar, alternate mouths having their centers on one line and the intermediate mouths having their centers on the other line, and a guard plate supported by the carrier bar over said yarn tubes and having circular perforations registering with said mouths.

20 8. In an Axminster tube frame having a carrier bar, a series of yarn tubes mounted on the bar, each tube having a yarn receiving mouth formed as an isosceles triangle, the sides of adjacent mouths lying along and closely adjacent to each other, the bases of alternate triangular mouths extending along close to said carrier bar and the bases of the intermediate triangular mouths 30 being parallel to but spaced farther from the bar than the first named bases.

25 9. In an Axminster tube frame having a carrier bar, a series of yarn tubes mounted on the bar, each tube having a yarn receiving mouth formed as an isosceles triangle, the bases of alternate triangular mouths extending along close to said carrier bar and the bases of the intermediate triangular mouths being parallel to but spaced farther from the bar than the first named bases, and 35 a guard plate supported by the carrier bar over said yarn tubes and having perforations registering with said mouths.

30 10. In an Axminster tube frame having a carrier bar, a series of yarn tubes mounted on the bar, each tube having a triangular shaped yarn receiving mouth, the sides of adjacent mouths lying along and closely adjacent to each other, the mouths of adjacent yarn tubes being reversed 40 with respect to the carrier bar.
